UNITED STATES PATENT OFFICE

ALEXANDER H. BEACH AND RALPH H. BEACH, OF FLINT, MICHIGAN.

WAGON-POLE.

SPECIFICATION forming part of Letters Patent No. 291,131, dated January 1, 1884.

Application filed April 19, 1883. (No model.)

To all whom it may concern:

Be it known that we, ALEXANDER H. BEACH and RALPH H. BEACH, of Flint, in the county of Genesee and State of Michigan, have invented new and useful Improvements in Wagon-Poles; and we do hereby declare that the following is a full, clear, and exact description thereof, reference being had to the accompanying drawings, which form a part of this specification.

The invention relates to certain new and useful improvements in the construction of wagon-poles, by means of which a pole of greater strength and lighter in weight is obtained than the poles which are ordinarily made.

The invention consists in the peculiar construction of the same, as more fully hereinafter described.

Figure 1 is a perspective view of our improved pole detached. Fig. 2 is a cross-section.

In the accompanying drawings our improved pole is shown constructed as follows: Sheet metal, (preferably steel plates,) of a suitable length for the pole, are employed, and bent by stamping-works or otherwise into a three-sided box of unequal dimensions at different portions of its length. This box A, which forms the top and sides of the finished tongue, tapers from its smallest cross-section at the front end, where it is designed to be engaged with the neck-yoke or other holdback appliances, and increases in size upon a true

taper to the point a, being the point where ordinarily the hammer is inserted, and thence tapering gradually to its rear end. The space within the box is filled with light wood backing B, which may be secured there in any suitable or known way; or the iron-work may be shrunk on the wood by heating and cooling.

It will be readily seen that this tongue may be as readily adapted to all the various running-gears which are employed in wagon-building as can the ordinary tongue, while its strength is much greater, its weight much less, and its durability very much increased.

We are aware of Patent No. 173,025, of 1876, in which a hollow metallic tongue having a longitudinal flange is set forth, and such construction is not sought to be covered in this application.

What we claim as our invention is—

As a new article of manufacture, a wagon-tongue formed of a continuous strip of sheet metal, bent into rectangular form in cross-section to give closed sides and top with open bottom, filled in with a wooden backing, and having longitudinal taper in opposite directions from the point a, substantially as described.

ALEXANDER H. BEACH.
RALPH H. BEACH.
